LAMP SHADE MOUNTING MEANS

Paul Chilo, Chicago, Ill.

Application March 12, 1938, Serial No. 195,456

8 Claims. (Cl. 240—148)

My invention relates to lamps equipped with shade supporting fixtures in the form of a harp wherein the shades may be rocked or tilted on their supports.

One of the objects of my invention is to provide a device of but few parts, inexpensive to construct and assemble and which will function in combination to hold the shade positively in any desired tilted position on its support against the vibrations or jars to which lamps are frequently subjected when in use.

It is another object of my invention to provide a construction so arranged that the supporting harp may be completely formed or made and the shade holding means thereafter be easily assembled and installed thereon.

My invention preferably contemplates a supporting harp having a top cross bar and side arms depending therefrom and it is a further object of my invention to provide a shade mounting or holding means of spring material having a central plate portion swingably mounted on the cross bar and arms adapted to bear with considerable spring pressure against the respective arms of the supporting harp, there being on one of the arms a series of depressions in any one of which the coengaging arm may be disposed thereby positively locking the shade holding means at the desired angle with respect to the supporting harp.

The invention consists of the novel constructions, arrangements and devices to be hereinafter described and claimed for carrying out the above stated objects and such other objects as will appear from the following description of a preferred embodiment of the invention illustrated in the accompanying drawing, wherein:

Fig. 1 is an elevational view of a lamp equipped with shade supporting means embodying the principles of my invention;

Fig. 2 is a side elevational view on an enlarged scale of the shade holding means;

Fig. 3 is a plan view of the parts shown in Fig. 2;

Fig. 4 is a sectional view taken on the line 4—4 of Fig. 3; and

Fig. 5 is a sectional view taken on the line 5—5 of Fig. 3.

Like characters of reference designate like parts in the several views.

The lamp 10 is provided with a shade support 11 which is generally in the form of a harp, the electric lamp bulb 12 being positioned within the harp and screwed into the lamp socket in the usual manner.

The supporting harp at its upper end is provided with a cross bar 11a and side arms 11b as best shown in Fig. 4.

The shade holding means comprises a central plate 13, and integrally formed therewith are arms 14. The parts 13 and 14 are formed to provide a slot 15 adapted to receive the cross arm 11a of the supporting harp. A disc 16 is positioned over the plate 13, the two parts being secured together with the cross arm therebetween by turning over the edge portion 16a of the disc 16. A mounting element in the form of a threaded stud 17 is provided with a collar 18 adapted to bear against the upper face of the disc 16, the lower end of the stud extending through an opening 16b in the disc 16 and then being riveted over or upset at 17a against the under side of the disc to secure the parts together.

A shade 19 is carried on a frame comprising a collar 20 and arms 21, the collar 20 being adapted to fit snugly around the collar 18 of the mounting stud 17. The shade is locked in position with the collar 20 bearing on the disc 16 by means of a nut or finial 22 threaded on the stud 17 against the collar 20 as clearly shown in Fig. 4.

It will now be apparent that the shade mounting means may be readily rocked on the cross bar 11a of the supporting harp. The means provided for locking the shade in the desired tilting position will now be described. In the embodiment illustrated, the arms 14 are in the form of segments as clearly shown in Fig. 2 and are provided with a series of depressions 23. The spring arms 14 if unrestrained are spaced much farther apart than the distance between the rigid arms 11b and the arms 14, therefore, bear with considerable spring pressure against the inner sides of the respective arms 11b of the supporting harp, said arms 11b being adapted to rest in any one of the adjacent depressions 23. In order to limit the extent to which the shade may be tilted, stops 24 are provided on the extreme ends of the segmental arms 14. The relation between the stops 24 and the depressions 23 with respect to the adjacent arms 11b is clearly shown in Fig. 4.

It will be apparent that the shade holding means described is well adapted for its purpose. The parts are inexpensive to construct and can be readily assembled and mounted on the harp support after the latter has been completely formed which facilitates factory production since the harp supports may be formed independently of the shade mounting means. The

spring arms 14 bear securely against the arms 11b of the harp support and in use effectively hold the shade tilted at the desired angle notwithstanding jars and vibration to which lamps 5 are generally subjected.

I do not intend to limit the invention to the details of construction shown and described, except only in so far as certain of the appended 10 claims are specifically so limited, as it will be obvious that modifications may be made without departing from the principles of the invention.

I claim:

1. In a shade support for lamps, the combination of supporting means including a cross bar and an arm at each end thereof, holding means of spring material swingably mounted on said cross bar between said arms and having arms initially spaced farther apart than the first 20 named arms and adapted to coengage with said first named arms, said holding means including a plate portion provided with a slot in which said cross bar is disposed, and a shade mounting plate disposed over said cross bar and having its edges 25 turned against the bottom of said plate portion.

2. In a shade support for lamps; the combination of an upstanding supporting frame including a top cross bar portion and side arms extending downwardly therefrom; holding means swingably mounted on said cross bar portion and including a downwardly extending arm; means for holding said last named arm in firm contact with one of said first named arms; and a shade mounted on said holding means and extending downwardly and around said cross bar portion, holding means, and arms; one of said contacting arms having a series of depressions for receiving the other of the contacting arms and for maintaining the shade in the desired adjusted position.

40 3. In a shade support for lamps; the combination of an upstanding supporting frame including a top cross bar portion and side arms extending downwardly at each end therefrom; holding means of spring material swingably mounted on said cross bar portion between said arms and including downwardly extending spaced arms adapted to coengage with the respective first named arms; and a shade mounted on said holding means and extending downwardly and around said cross bar portion, holding means, and arms; one of said arms having a series of depressions in any one of which the adjacent coengaging arm 45 may be positioned for maintaining the shade at the desired angle.

55 4. In a shade support for lamps, the combination of an upstanding supporting frame including a top cross bar portion and side arms extending downwardly at each end therefrom; holding means of spring material swingably mounted on said cross bar portion between said arms and including downwardly extending spaced arms adapted to coengage with the respective first named arms; and a shade mounted on said holding means and extending downwardly and around said cross bar portion, holding means, and arms; one of said arms being in the form of a segment 60 and having spaced stops between which the coengaging arm may swing, said segment having a series of depressions for receiving the adjacent 65 co-engaging arm for maintaining the shade at the desired angle.

5. In a shade support for lamps; the combination of an upstanding supporting frame including a top cross bar portion and side arms extending downwardly at each end therefrom; holding means of spring material swingably mounted on said cross bar portion and including downwardly extending spaced arms adapted to coengage with the respective first named arms; and a shade mounted on said holding means and extending downwardly and around said cross bar 10 portion, holding means, and arms; one of said arms having a series of depressions in any one of which the adjacent coengaging arms may be positioned, the outermost arms being so spaced with respect to the innermost arms that a strong 15 spring pressure is maintained between the coengaging arms thereby holding the shade in the desired adjusted position.

6. In a shade support for lamps; the combination of an upstanding supporting frame including a top cross bar portion and side arms extending downwardly at each end therefrom; holding means of spring material swingably mounted on said cross bar portion between said arms and including downwardly extending arms 20 initially spaced farther apart than said first named arms and so adapted when assembled as to spring strongly against and coengage said first named arms; and a shade mounted on said holding means and extending downwardly and around 25 said cross bar portion, holding means, and arms; one of said arms having a series of depressions in any one of which the adjacent coengaging arm may be positioned thereby maintaining the shade in the desired adjusted position.

35 7. In a shade support for lamps; the combination of an upstanding supporting frame including a top cross bar portion and side arms extending downwardly therefrom; holding means of spring material swingably mounted on said cross 40 bar portion between said arms and including downwardly extending arms initially spaced farther apart than said first named arms and so adapted when assembled as to spring strongly against and coengage said first named arms: 45 and a shade mounted on said holding means and extending downwardly and around said cross bar portion, holding means, and arms; one of said second named arms being in the form of a segment with the lower edges thereof being flanged, 50 said flanges having a series of depressions in any one of which the adjacent coengaging arm may be positioned, thereby maintaining the shade in the desired adjusted position.

8. In a shade support for lamps; the combination of an upstanding supporting frame including a top cross bar portion and side arms extending downwardly at each end therefrom; holding means of spring material swingably mounted on said cross bar portion between said arms and 60 having downwardly extending arms initially spaced farther apart than the first named arms; said holding means including a plate portion provided with a slot in which said cross bar portion is disposed and a mounting plate attached 65 to said plate portion; and a shade mounted on said mounting plate and extending downwardly and around said cross bar portion, holding means, and arms.
